HUMPTY-DUMPTY INFLATABLE TOY

Anna L. Oehs, Indianapolis, Ind.

Application May 27, 1953, Serial No. 357,855

2 Claims. (Cl. 46—87)

1

This invention relates to a toy herein shown in one form as a Humpty Dumpty and involves the use of an outer fabric casing which is made up of a number of individual parts and so sewed together as to form the configuration of the Humpty Dumpty, and also which will provide means for mounting and holding arms and legs in a manner which will keep them extended from the overall body. The invention further contemplates the use of a rubber balloon which may be inserted inside of the casing through a small opening, and then permits the balloon to be inflated through a neck which extends out through the casing to permit its tying off and to afford a permanent extension as long as the balloon is inflated.

A primary feature of the invention is to provide a changeable cover or casing which may be cleaned such as by dry cleaning or actual washing, and also which may be replaced by other casings of different caricatures. A still further important object of the invention is to provide a structure wherein the stem of the inflatable balloon affords a post or pedestal for holding a hat on the toy to have the crown held against permanent distortion, and which will permit ready access to that stem for inflation or deflation without having to disturb any other part of the toy with the exception of lifting the hat from over the balloon stem.

Still further objects and advantages of the invention reside in the fact that trimmings of the toy, such for example as a collar, may be held in such manner that it will extend upwardly from its attachment to the casing, in order to maintain the collar-like appearance of this element. That is, by the structure employed in mounting the collar on the toy, the collar will always be maintained in an upright rather than in a drooping or bedraggled condition.

Obviously, by using the ordinary toy balloon, the degree of inflation may be had readily by blowing the balloon up to that degree of firmness desired, and moreover should the balloon spring a leak or actually blow out, the balloon may be readily replaced. In this regard, the toy balloon is inserted through the head or top end of the casing through an extremely small orifice so that the balloon will be maintained within the casing for all practical purposes through its entire contour with the exception of the stem through which the balloon is inflated.

These and many other objects and advantages of the invention will become apparent to those versed in the art in the following description of the one particular form of design as illustrated in the accompanying drawings, in which

Fig. 1 is a view in front elevation of a device embodying the invention;

2

Fig. 2 is a view in bottom plan;

Fig. 3 is a detail in vertical section on an enlarged scale on the line 3—3 in Fig. 1;

Fig. 4 is a detail on an enlarged scale in vertical section of the leg and arm attaching structure;

Fig. 5 is a view in side elevation and partial section of the structure;

Fig. 6 is a view in top plan with a portion of the covering hat removed;

10 Fig. 7 is a view in side elevation of the rubber balloon; and

Fig. 8 is a view in vertical section on an enlarged scale on the line 8—8 in Fig. 5.

The overall configuration of the toy is ovoid in nature, and it is formed out of any suitable or desired fabric by sewing together a plurality of gores. There are a plurality of upper and lower gores, all of the gores being united in a common, small circle below the center of the toy.

15 20 An upper, front gore 10 is defined by the lines ABCD. The line AB may be a straight line whereas the lines AC and BD are arcuate in nature to provide for the resultant, desired curvature. A rear gore 11 is formed to have substantially the same dimensions and contour as that of the front gore 10. This rear gore 11 is defined by the lines EFHG. It terminates on the small circle by the line GH. Then to complete the upper portion of the toy, there are provided the two side gores 12

25 30 and 13. These side gores are substantially equal in size and configuration to the front and back gores 10 and 11. The side gore 12 is defined by the lines FBDH and the other side gore 13 is defined by the lines AEGC. The side gores 12 and

major portion of the arm 19 being hollow and stuffed with some material 20, such as cotton batting or the like, but this stuffing terminates on some approximate line, such as the line LM so as to leave a flat tab portion 21 which is carried between the front gore 10 and the left side gore 12 and united to those gores by stitching of the hem all as indicated in Fig. 4. That is, the tab 21 lies between the inturned end portion 22 of the side gore 12 and the inturned portion 23 of the front gore portion 10, and stitching 24 extends through these portions 22 and 23 and the intervening tab 21. Thus the arm 19, while having a rounded major proportion, has the flattened tab 21 secured to the toy, so that the arm 19 may hinge forwardly and rearwardly on that tab just outside of the zone of emergence of the arm 19 from between the two gores 10 and 12. In like manner, a right hand arm 25 is secured between the gores 10 and 13, both arms 19 and 25 being located above the small circle line generally designated by the numeral 26, Fig. 1, and also in like manner there are legs 27 and 28 attached between the respective gores 15, 16 and 15, 18 to extend outwardly and downwardly as best indicated in Fig. 1.

The gore 10 is provided with a face painted or printed thereon, in any suitable manner, herein shown as in the general style of the Humpty Dumpty. The imprinted matter or painted on matter may of course vary as may be desired.

A collar, generally designated by the numeral 30, is centered on the front gore 19 and carried around to substantially the central zones of the side gores 12 and 13, and is confined to the doll to extend upwardly from the small circle 26. By reason of the peculiar mounting of this collar 30, it is maintained in an outwardly and upwardly extending position when the overall housing or casing, designated by the numeral 31, is inflated as will hereinafter be explained. The collar 30 is mounted to extend, on the small circle 26, inwardly between the upper and lower gores 13, 18, 10, 15, and 12, 16, and by an inwardly extending portion designated by the numeral 32, Fig. 8, is interengaged between the inwardly extending portions 33 and 34 of the upper and lower gores, such as gores 13 and 12, Fig. 8, by any suitable means, such as by stitching 35. The collar 30 is best formed by a double thickness of material having an outer fold 36. Thus by reason of the eventual curvature of the overall casing 31, the collar 30 will be secured to extend upwardly and outwardly from the circle 26. As a finishing touch, a bow tie 37 is attached to the lower gore 15 at the center of the collar 30, the collar 30 preferably being of the wing type with the overturned tabs 38 and 39.

A rubber balloon 40, Fig. 7, is provided in the usual manner with an inflating neck 41. The balloon 40 being of a very thin wall structure is inserted through the top opening ABFE, Fig. 6, to have the major portion of the balloon carried into the inside of the casing 31, while the stem 41 is held outwardly of the casing 31, so that the balloon may be inflated by blowing through this neck 41, this operation causing the balloon 40 to be inflated inside of the casing 31, and thus extend the casing to its predetermined form as defined and permitted by the shapes of the various gores united as above explained. When the desired degree of inflation has been had, the neck 41 may be tied off by any suitable means, such as by a rubber band 42, Fig. 5, in which case the

neck 41 will remain in a position extending from the casing 31.

Now to complete the toy, a hat generally designated by the numeral 44 is provided to cover over the opening ABFE and also to cover over the stem 41. Preferably this hat 44 is secured to the casing 31 such as by stitching 45 going through the brim 46 of the hat and through the upper portion of the back gore 11, Fig. 6. This provides roughly a hinging line of the hat on the casing 31. The brim 46 carries a central crown 47 which is somewhat cylindrical in shape and sufficiently large at least to freely encircle and enclose the balloon stem 41, Fig. 5. The hat 44 is retained in position by any suitable securing means carried by the forward end portion of the brim 46, herein shown as by the usual and well-known glove fastener means 48, as illustrated in detail in Fig. 3, wherein the front gore 10 carries the post or button 43 of the fastener, and the brim 46 carries the spring-cup 50 into which the post 49 springs, all in the usual and well-known manner.

Thus it is to be seen that the stem 41 normally extends well within the crown 47 of the hat 44, and roughly supports that crown 47 against complete downward or sidewise crushing, and also the crown 47 covers over the stem 41 so as to complete the artistic appearance of the overall toy. Access to the stem 41 is quickly had by lifting up on the forward end of the brim 46 to disengage the fastener 48 so that the hat can be swung back on the stitching 45.

Therefore, while I have described my invention in minute detail in the one particular form, it is obvious that structural changes may be employed without departing from the spirit of the invention, and I therefore do not desire to be limited to that precise form beyond the limitations imposed by the following claims.

I claim:

1. An inflatable toy comprising a substantially inelastic casing having a plurality of gores intersecured along marginal edge portions and having an opening between the gores at an end of the toy; legs and arms extending between said gore edge portions and secured therebetween; an elastic balloon having a neck portion and carried within the casing with said neck portion extending through said opening, said balloon being collapsible for insertion and removal through the opening; a hat hinged to the casing and having a crown receiving and covering said neck therein; means detachably holding the hat in position over said neck; said gores defining, when extended by said balloon, a generally ovoid figure and the gores being divided into upper and lower gores and united along a small circle below the center of the figure, and a collar being secured to the figure to extend around a front curving portion thereof and extending upwardly from said small circle.

2. The structure of claim 1 in which said collar enters by a lower edge portion between said upper and lower gores to be held therebetween.
